US00D567086S

(12) **United States Design Patent** (10) **Patent No.:** **US D567,086 S**
Buchman et al. (45) **Date of Patent:** **** Apr. 22, 2008**

(54) **TWIST OFF LID**

(75) Inventors: **James E. Buchman**, Hortonville, WI (US); **Erica L. Gretz**, Appleton, WI (US)

(73) Assignee: **Reynolds Consumer Products, Inc.**, Richmond, VA (US)

(**) Term: **14 Years**

(21) Appl. No.: **29/284,171**

(22) Filed: **Aug. 31, 2007**

(51) **LOC (8) Cl.** **09-07**

(52) **U.S. Cl.** **D9/454; D9/453**

(58) **Field of Classification Search** D9/780, D9/763, 539, 516, 454, 453, 449, 447, 440, D9/439, 438, 436, 435, 452; D34/39; 222/570, 222/569, 547, 464.1, 185.1, 565; 220/257.1; 215/341; 137/845, 844; D7/392, 392.1, D7/505; D32/54

See application file for complete search history.

(57) **CLAIM**

The ornamental design for twist off lid, as shown and described.

DESCRIPTION

FIG. 1 is a perspective view of a twist off lid according to our new design;

FIG. 2 is another perspective view of the twist off lid of FIG. 1;

FIG. 3 is a front elevational view thereof;

FIG. 4 is a rear elevational view thereof;

FIG. 5 is a top plan view thereof;

FIG. 6 is bottom plan view thereof;

FIG. 7 is a right elevational view thereof; the left elevational view being a mirror-image thereof;

FIG. 8 is a perspective view of a second embodiment of a twist off lid made according to my new design, the portions shown in broken lines forming no part of the design sought to be patented;

FIG. 9 is another perspective view of the twist off lid of FIG. 8, the portions shown in broken lines forming no part of the design sought to be patented; and

FIG. 10 is a top plan view of the embodiment of FIG. 8, the portions shown in broken lines forming no part of the design sought to be patented; and,

FIG. 11 is a bottom plan view of the embodiment of FIG. 8, the portions shown in broken lines forming no part of the design sought to be patented.

The front elevational, rear elevational, left elevational, and right elevational having the same appearances as FIGS. 3, 4, and 7, respectively.

1 Claim, 8 Drawing Sheets
